UNITED STATES PATENT OFFICE.

MICHAEL ANDREW DROITCOUR, OF DELPHOS, OHIO.

SHEET-DELIVERY MECHANISM.

1,303,040.

Specification of Letters Patent.

Patented May 6, 1919.

Application filed March 8, 1918. Serial No. 221,186.

To all whom it may concern:

Be it known that I, MICHAEL A. DROITCOUR, a citizen of the United States, residing at Delphos, in the county of Allen and State 5 of Ohio, have invented certain new and useful Improvements in Sheet-Delivery Mechanism; and I hereby declare that the following is a full, clear, and exact description thereof, reference being had to the accompanying drawings, which form part of this 10 specification.

This invention relates to sheet-printing presses and the like to which the sheets are fed preferably by an automatic feeder, 15 printed and automatically delivered.

The principal objects of the invention are:

To deliver the sheets of paper from the machine so that they will be piled and need not be handled except in a pile, thus allowing 20 the machine to have a more continuous operation; and the sheets are delivered in such manner that the joggers can work properly on each sheet as it is deposited on the pile.

To provide novel means for depositing the sheet upon the receiving table, either by means of tapes with the printed side up, or by means of a fly with the printed side down.

To provide a novel extended sheet delivery including a movable set of tapes whereby the sheet is carried over the receiving table and deposited thereon, the movable set of tapes not being traveled on the outward 35 or sheet-carrying movement but being so traveled on the inward movement that the top runs of the tapes withdraw from beneath the sheet, letting it drop upon the receiving table or board.

To provide novel means for jogging or straightening the sheets as they are deposited upon the receiving pile or table, and to provide means whereby the joggers can be readily adjusted to suit various sizes of 40 sheets without the necessity of stopping the press, or of the operator having to reach into the delivery mechanism in order to adjust the joggers.

To provide novel means for holding sheets 50 of paper in frictional contact with the tapes of the sheet carrier so that the sheet will not slip or slide on the tapes out of proper position.

To provide novel means whereby the pile 55 of printed sheets may be gradually lowered;

and to provide means whereby the descent of the delivery table is controlled by the ascent of the pile of unprinted sheets in the feeding mechanism.

This invention, in brief, includes novel 60 means and combinations of parts for delivering the sheets either by tapes or by a fly; novel means for lowering the pile of printed sheets as and in accordance with the elevation of the pile of unprinted sheets; 65 novel jogging devices, and novel means for operating the same; and other novel features and combinations of parts hereinafter explained.

To enable others to understand and utilize 70 the invention, I will describe one practical embodiment thereof as illustrated in the accompanying drawings; but I do not consider the invention restricted to such particular application thereof or to the specific construction of parts illustrated in said drawings; and have set forth in the claims the 75 essential features and novel combinations and novel constructions of parts for which protection is desired.

In said drawings:

Figure 1 is a top plan view of the delivery mechanism of a printing press, or other sheet handling machine, embodying the invention; some of the parts that are shown 85 in Fig. 2 being omitted for the sake of clearness.

Fig. 2 is a side elevation of Fig. 1, some of the parts shown in Fig. 1 being omitted for the sake of clearness.

Fig. 3 is a diagrammatic side elevation of parts of the feeding, printing and delivering mechanisms of a machine for operating upon sheets, such as a printing press, showing the operative connections between the 95 parts pertaining to the present invention.

Fig. 4 is a detail side elevation showing the mechanism for operating the reciprocating tape carriage.

Fig. 5 is an enlarged detail sectional view 100 of the clutch devices for actuating the tapes on the said carriage.

Fig. 6 is a section on lines 6—6, Fig. 5.

Fig. 7 is an enlarged plan view of the means for driving the shaft 7^a from the 105 shaft 5^a.

Fig. 8 is a side elevation of Fig. 7.

Fig. 9 is an enlarged plan view of one of the jogger operating devices.

Fig. 10 is a sectional end view of Fig. 9. 110

Figs. 11 and 12 are enlarged detail views of the devices for operating the delivery board from the feed mechanism.

Figs. 13 and 14 are details.

5 Fig. 15 is a detail section on line 15—15, Fig. 4.

I will explain the invention as applied to a sheet printing press and in the drawings have shown only so much and such 10 parts of the press and the feeding and delivery mechanisms thereof as are necessary to enable those familiar with such machines to readily understand the invention.

15 *The movable sheet delivery tapes.*

The sheets of paper, after they have been fed to the press and operated upon thereby, are advanced from the printing mechanism by means of endless tapes 1 the outer ends of 20 which run over pulleys 1^a on a shaft 1^b, mounted in suitable bearings 1^x attached to the side members of the supporting framing.

Intermediate these tapes 1 are a set of 25 tapes 2 which run over pulleys 2^a on shafts 2^b, journaled in bearings in a carriage which may be composed of side members 2^c and end bars 2^d, as shown; or of any suitable construction, and said carriage is supported by rollers 2^e on bars 2^f attached to the sides of 30 the supporting frame.

The carriage is adapted to be reciprocated longitudinally of the tapes 1; and the upper runs of tapes 2 are in substantially the same plane as the upper run of the tapes 1, and 35 when the carriage is in its innermost position (see Fig. 1) and a sheet has been brought forward by tapes 1, the carriage is moved outward so that said tapes 2 will receive the sheet from tapes 1 and carry such 40 sheet on outward and over the receiving table 3 hereinafter referred to (see Fig. 3). When the carriage is moved inward, the shafts 2^b are rotated so that the upper runs of the tapes 2 remain practically stationary 45 and said tapes withdrawn from beneath the sheet allowing it to drop upon the receiving table. The reciprocating tape carriage may be of any suitable construction and the tapes may be actuated by various mechanisms so 50 timed as to cause the tapes to deposit the sheets upon the receiving table in the manner stated.

In the example shown, each side member 2^c of the carriage may be provided with a 55 rack 2^g meshing with a gear 2^h on a shaft 2ⁱ which is driven by a bevel gear 2^j meshing with a bevel gear 2^k on a shaft 2^l, which shaft may be operated by suitable gearing from any suitable part of the machine or 60 press to which the delivery is attached so that the set of tapes 2 will be reciprocated back and forth at the proper time to receive and deposit the sheet onto the receiving table.

The shaft 2^l when attached to a printing 65 press may be operated by means of a beveled

gear 12 on its inner end meshing with a beveled pinion 12^a on a stud shaft 12^b (see Fig. 4) to which beveled pinion 12^a is attached a gear pinion 12^c, that meshes with a rack bar 12^d which in turn engages a gear 12^e mounted 70 on a shaft 12^f carrying a pinion 12^g meshing with a rack 12^h, that carries a cam roller 12ⁱ engaging a race cam 12^j mounted on a driven shaft 12^k, which may be mounted in the press frame and so geared to the press 75 operating mechanism or drive shaft that cam 12^j through the described connections will impart a reciprocatory motion to the tape carriage 2^c at the proper time so that the set of movable tapes 2 will be advanced 80 and retracted in the proper time and manner in relation to the delivery of the printed sheets from the press.

The tapes 2 are not traveled as the carriage moves outwardly over the receiving 85 table, but are traveled to withdraw from beneath the sheet when the carriage is drawn inward. To operate the tapes 2 in this manner (see Figs. 5 and 6) one of the shafts 2^b may have a ratchet housing 2^m keyed thereon, in which is a ratchet or roller clutch member 2ⁿ attached to a gear 2^c, both loosely mounted on a shaft 2^b; gear 2° meshes with a stationary rack 2^p attached to the side frame of the machine, and said clutch is so 90 arranged that when the set of tapes 2 is moved outward the clutch 2ⁿ rotates idly in the housing, being then disengaged therefrom; but when the set of tapes is moved inward the clutch is engaged and the shaft 2^b 100 rotated from beneath the sheet and let the same drop upon the receiving table in the manner described.

In order to prevent the sheets of paper sliding on the tapes 2 while they are being 105 moved outwardly to carry the sheet over the receiving table, and to prevent the sheets over-running or sliding beyond their proper position on such tapes at the end of the outward movement thereof, I preferably employ an air blast or jets of air directed 110 downwardly against the sheet of paper lying on the tapes 2 and being moved outward thereby; and for this purpose a preferably perforated air blast pipe 12 is arranged 115 above the set of tapes 2, as indicated in Figs. 1 and 2, said air blast pipe being suitably supported in any convenient manner and preferably disposed horizontally above and transversely across the movable set of tapes 120 2. Said blast pipe may be connected by pipe 12^a to a suitable air blower or compressed air supply, not shown. The blast of air is directed downwardly onto the sheet S lying on the tapes 2, as the latter are moved outwardly, and such blast causes a frictional contact between the sheet and the tapes, and when the tape carriage is slowed down and stopped, preparatory to its inward movement, the sheet of paper S being held in fric- 125 130

tional contact with the tapes 2 by the air blast will not over-run or slide beyond its proper position. Such air blast enables the delivery mechanism to be operated satisfactorily and at high speed.

The delivery cam 12^j which operates the carriage carrying the tapes 2 is preferably circular, but set eccentric to the shaft 12^k; and the cam is so placed that it will cause the carriage to dwell longer when in its innermost position as shown in Fig. 1, than when in its extreme outermost position over the delivery table. In practice the cam shown will cause the tapes when in their innermost position to dwell during approximately a half revolution of the cam, while during the next half revolution of the cam the tapes are moved outward, stopped and again moved inward. The object of such unequal dwells is to allow each sheet time to settle toward the pile after it is dropped by the tapes before the next outward stroke of the carriage so that upon the next outward movement of the tape carriage the tapes or carriage parts will not contact with the rear end of the sheet that has just been delivered.

Sheet receiving devices.

The sheets taken by the set of movable tapes 2 are dropped upon a receiving board or table 3. As the pile of paper increases in height, due to the sheet dropping on this board, the top of the pile is automatically maintained approximately at the same level.

The board 3 may be removably mounted upon angle-irons 3^a attached to endless chains 3^b running over sprockets 3^c attached to upper and lower shafts 3^d and 3^e journaled in bearings attached to the framing; and said shafts may be operated by means of worm gears 3^b on a shaft 3^e engaging worm 3^f on a shaft 3^h, carrying a bevel gear 3ⁱ, meshing with a bevel gear 3^j on a shaft 3^k, which is preferably operated, as hereinafter described, so as to lower the board 3 at the same speed as the pile of sheets are elevated in the feeder at the feed end of the machine.

I preferably operate the receiving table from and by the means used to lift the pile in the feeder. This feeder mechanism may be used as shown in my Patent No. 1,146,929 of July 20, 1915, or of any suitable construction, in which the sheets are fed from a pile placed on a table which is gradually raised as the sheets are removed therefrom. In this feeder the pile of sheets is placed upon a table 3^z, which is elevated gradually as the sheets are removed therefrom and fed to the press.

The shaft 3^l which operates the means for lowering the receiving table 3 is preferably extended as indicated in Fig. 3, to and beneath the table of the automatic feeder, and shaft 3^k may have on its end below the feed table 3^z a bevel gear 3ⁱ meshing with a corresponding gear 3^m loosely mounted on a

shaft 3^a, which is operated by means of a ratchet 3^r engaged by a pawl 3^s on an oscillating lever 3^t which may be actuated by a rod 3^u from a suitable power-actuated part of the press or feeder as described in my aforesaid patent. Loosely mounted on shaft 3^a beside ratchet 3^r is a similar ratchet 3^w, which is also engaged by the pawl 3^s and is fast to gear 3^m so that when the pawl 3^s is operated both ratchets 3^r and 3^w will be operated and shafts 3^a and 3^k will be turned. Shaft 3^a carries a worm 3° operating the worm gear 3^p on the shaft 3^q that operates the chains 3^y carrying the feed table 3^z and pile of sheets thereon.

By this means the delivery table 3 is operated and lowered as and just in proportion to the upward movement of the feed table 3^z. In this way any possibility of the operator forgetting to lower the delivery table is eliminated and a great saving of printed paper is effected.

By disengaging pawl 3^s the sheet delivery table may be operated by hand, to either lower or raise the pile, without operating the feeder pile or disarranging the adjustment of that part of the mechanism, so that if the operator desires to remove a pile of paper from the delivery table and wishes to lower this pile onto a truck, he can do this without affecting the feeder pile; and he can also reload his feeder table and make the necessary adjustments of the feeder pile without disturbing the delivery.

For this purpose double ratchets 3^r and 3^w are used with one common wide-faced pawl 3^s which engages both wheels. The independent turning of either one of these ratchets 3^r 3^w does not affect the other ratchet except when both are engaged and operated by the pawl 3^s at which time the delivery is connected with the feeder through the pawl. The feeder pile raises and the delivery pile lowers automatically only when same are actuated by the mechanisms provided, and raising or lowering either pile by hand does not affect the other, or vice versa.

Sheet jogging devices.

The leading edges of the sheets are alined against gages or stops 4, carried by the member 4^a attached to the framing as they are deposited on the board 3. The sheets are pushed against the stops 4 by means of joggers 5 which are supported by short rack bars 5^a that are guided in castings 5^b supported adjacent the inner edge of the board. The rack bars 5^a are engaged by pinions 5^c on a rotatable shaft 5^d which is supported in bracket castings 5^e and 5^f that are slidably mounted upon the side members 6^e and 6^f of the framing.

The brackets 5^b (see Figs. 1, 9 and 10) are slidably mounted upon the shaft 5^d and fastened on a tubular shaft 6, which is fastened

to the castings 5^e, 5^f. Through this tubular shaft 6 extends a shaft 6^a which carries pinions 6^b on its ends, engaging racks on or attached to the under side of the side member 6^e and 6^f on which the castings 5^e and 5^f are mounted. (See Fig. 13.) The shaft 6^a is provided with a hand wheel 6^d by which it can be turned to adjust the joggers 5 longitudinally of the supports 6^e, 6^f, toward or from the stops 4 to suit different sizes of sheets; but all the joggers remain at the same height, and the pile of sheets is lowered beneath the joggers, as the pile increases as above described.

15 The shaft 5^d may be oscillated by suitable means so as to reciprocate the rack bars 5^a longitudinally and impart the desired motion to the joggers 5 by any suitable means. In the example shown the shaft 5^d has on one end a bevel gear 5^e meshing with a bevel gear 5^h (Fig. 1) splined on a shaft 5ⁱ and journaled beside the side bar 6^e. Gear 5^h is caused to move with the casting 5^e by means of a yoke 5^k attached to the casting 5^e and embracing the gear 5^h, as indicated in the drawing. The shaft 5ⁱ may be operated by any suitable means so as to move the joggers at the proper times and manner to adjust the sheets on the side. As indicated in Figs. 1 and 2, shaft 5ⁱ has an arm 5^v on one end connected by a rod 5^w to one arm of a bell crank lever 5^x pivoted on the framing, and having its other arm connected by a link 5^y to a lever 5^z also pivoted on the framing 35 and preferably provided with a roller engaging a cam 5^u on a shaft 5^t which may be one of the press shafts or driven therefrom so that the joggers are operated at the proper time. The shaft may be positively 40 rocked in one direction by the action of the cam, and in the other direction by the action of a spring conventionally indicated at 5^s in Fig. 2.

The side joggers 7 are constructed and operated substantially like the joggers 5. Each jogger 7 is supported by rack bars 7^a, mounted in castings 7^b and engaging pinions 7^c on a shaft 7^d, which is journaled in brackets 7^e and 7^f mounted on members 8^e and 8^f of the framing. The brackets or castings 7^b are supported on shaft 7^d and a tubular shaft 8, which is attached to the castings 7^e and 7^f. In the tubular shaft 8 is a shaft 8^a carrying pinions 8^b which mesh with racks in or attached to the members 8^e and 8^f; and shaft 8^a has a hand wheel 8^d by which it can be turned; and when this shaft is turned the joggers 7 are adjusted toward or from the opposed jogger. By means of the hand 55 wheels 6^d, 8^d, the operator is able to move the joggers to accommodate varying sizes of sheets without stopping the press and without getting any parts out of time.

60 The joggers 7 may be reciprocated by any suitable means; preferably by means actu-

ated from the shaft 5^d. As shown in Figs. 1, 7 and 8 a pinion 7^b is splined on shaft 7^d and confined in an opening in a casting 7ⁱ hung on shaft 5^d. Pinion 7^b meshes with one toothed side of a rack bar 7^j slidably mounted in casting 7ⁱ, and having another toothed face meshing with a pinion 5^m on shaft 5^d and confined in an opening in casting 7ⁱ (see Figs. 7 and 8). This construction enables me to independently adjust the shafts 5^a and 7^d laterally to or from the board 3; while maintaining an operative geared relation between the said shafts.

The shafts 7^d and 8 are preferably arranged below the plane and at right-angles 80 to the shaft 6 and 5^d, but by using the double-faced connection, as shown (see Figs. 7 and 8) I am able to impart a rocking motion from the shaft 5^d to the shafts; and thus all the joggers 7 and 5 will be properly reciprocated upon the oscillation of shaft 5^d. This construction makes the action of the joggers 85 positive and smooth, so that when a sheet is pushed into position on the pile by the joggers there will be no offsetting of the ink 90 from the top sheet of the pile on to the back of the next sheet deposited thereon.

It is frequently necessary to change the position of the sheet guides on the press when same is running and such change 95 causes the following sheets to fall onto the receiving board 3 in a different position than the prior sheets, for which the joggers were originally set by the operator; but with the described construction the joggers can be 100 readily adjusted by means of the hand wheels 6^d and 8^d to suit the changed delivery 105 of the sheets; and this makes the machine safer for the operator, and allows the press to run while the joggers are being adjusted, thus saving much time.

The fly delivery.

In connection with the set of movable 110 tapes 2 which deliver the sheet printed side up, I provide a fly delivery which may be used to deliver the sheets printed side down in the well known manner.

When the fly is to be used the delivery 115 tapes 2 must be put out of action, and vice versa.

As shown in Fig. 1, the fly has a series of 120 fingers 9 arranged intermediate the tapes 1 and 2 and attached to a shaft 9^a journaled in suitable brackets 9^b on the main frame. On one end of this shaft is a pinion 9^b (Fig. 3) which can be operated by a rack or in any suitable manner, when it is desired to use the fly. The rack 9^c may be held in engagement 125 with the gear 9^b by a roller 9^d mounted on a stud attached to the framing.

On the shaft 9^a beside gear 9^b is a gear 130 which meshes with a rack 9^e that is held in mesh therewith by means of a roller 9^f mounted on the framing. This rack 9^e is con-

trolled by a spring 9^h that tends to move the rack in such a direction as to oscillate the shaft 9^a and turn the fly from position between the tapes 1 over so it will deliver the 5 sheets printed side down on the table 3. The rack 9^c may be actuated at the proper time so as to turn the fly to receiving position by any suitable means. Preferably the inner end 10 of rack 9^c is engaged with a pinion on a stud 9^m (see Fig. 3) which pinion is oscillated by a rack 9ⁿ pivotally connected to one arm of a bell crank lever 9° the other arm of which may carry a roller 9^p engaging a cam 9^q on a shaft 9^r, which may be one of the 15 press shafts (or be driven by suitable gearing from the mechanism of the press) so as to rotate the cam 9^q at the proper time to cause the rack 9^c to turn the fly to the normal position between the tapes 1 and 2 20 and hold the fly in this position until the sheet has been brought forward over the fly by tapes 1; and then, at the proper time, the cam permits the spring 9^h to actuate the fly and deliver the sheet. Then the cam 25 causes the bar to return the fly to normal position and holds it in such position until the next sheet has been brought forward on the tapes.

When the fly delivery is to be used the 30 movable set of tapes 2 should be put out of action by any suitable means; as by disengaging the gear 12^a from the gear 12^e. As shown in Fig. 4, said gears are normally interlocked by means of a bolt as 12ⁿ adjustably connected with gear 12^g and adapted to be engaged with a stud 12^q to oscillate together; but when bolt 12ⁿ is disengaged from gear 12^e the latter will be idled and the set of tapes 2 rendered inactive while 35 the fly is in use.

When the tapes are to be used the fly can be idled in any suitable manner; as shown in Fig. 3; a rod 9^u is pivoted to lever 9° and passes through a guide 9^v on the framing, 40 and has an adjusting nut 9^w on its outer end; and by adjusting this rod 9^u the lever 9° can be permitted to engage cam 9^q, when the fly is to be operated; or when the fly is not to be used it is so adjusted that roller 9^p cannot be engaged by the cam 9^q.

Operation.

The sheets are fed automatically from the feed table 3^z to the machine and operated upon, and are then delivered by the movable set of tapes 2 onto the board 3, and are positioned thereon by the joggers 5 and 55 7, which can be adjusted by means of hand wheels 6^a, 8^a to suit different sizes of sheets 60 while the machine is in operation. If it is desired, the movable tapes can be put out of operation and the sheets delivered by the fly 9. The board 3 is automatically lowered as the sheets are deposited thereupon, in

accordance with the depletion of the pile of 65 sheets on the feed table 3^z. All the parts are operated as hereinbefore explained.

I do not herein now claim the delivery table lowering mechanism nor the delivery and air blast mechanism, as these matters 70 form the subject of divisional applications.

I claim:

1. In sheet delivery mechanism having a receiving table or board, and a set of joggers, and means for actuating same:—means 75 whereby the joggers may be adjusted to or from the board while the machine is in operation without disarranging their operative mechanism.

2. In a sheet delivery mechanism having 80 a receiving table or board, end and side joggers, and supports for the said joggers, means for operating the joggers, and means for adjusting the joggers' supports while the machine is in operation, without disarranging 85 the jogger operating mechanism.

3. In a sheet delivery mechanism having a receiving table or board, and means for delivering sheets thereon; of end and side joggers, adjustable supports for the front 90 and end joggers, means for operating the joggers, and means for independently adjusting said supports while the machine is in operation, without disarranging the jogger 95 operating mechanism.

4. In sheet delivery mechanism having a receiving table or board, and means for delivering sheets thereon; of end and side joggers, adjustable supports for the front 100 and end joggers, means for operating one set of joggers, means for independently adjusting said supports while the machine is in operation without disarranging the jogger operating mechanism, and operative 105 connections between the sets of joggers whereby one set is actuated by and with the other.

5. In jogging mechanism, a shaft, a pinion splined thereon, a member movable longitudinally of the shaft, a rack bar slidably 110 mounted in said member and meshing with the pinion, and a jogger on said rack bar.

6. In jogging mechanism a pair of parallel shafts, means for moving said shafts laterally, a member slidably supported on 115 said shafts, a pinion slideable on one shaft and positioned by said member, means for operating the latter shaft, a rack bar slidably supported in said member and engaging said pinion, and a jogger attached to 120 said bar.

7. In jogging mechanism a pair of parallel shafts, slideable supports in which the shafts are mounted, means for moving said supports to adjust the shafts laterally, a 125 member slidably supported on said shafts, a pinion slideably keyed on one shaft and positioned by said member, means for operating

the latter shaft, a rack bar slidably supported in said member and engaging said pinion, and a jogger attached to said rack bar.

8. In jogging mechanism a pair of intersecting shafts, means for independently moving said shafts laterally, a member slidably connected with said shafts at their intersection, pinions on said shafts, and a double faced rack bar slidably supported in 5 said member and engaging said pinion whereby said shafts are caused to operate in unison.

9. In jogging mechanism, a pair of intersecting shafts, slidable supports for each 15 shaft, means for moving said supports to adjust the shafts laterally; a member slidably connected with said shafts at their intersection, a pinion slidably keyed on said shafts, and a double-faced rack bar slidably supported in said member and engaging said 20 pinions whereby said shafts are caused to operate in unison.

10. In jogging mechanism, a pair of intersecting shafts, slidable supports for each 25 shaft, means for independently moving said supports to adjust the shafts laterally, a member slidably connected with said shafts at their intersections, pinions slidably keyed on said shafts and positioned by said member, and a double-faced rack bar slidably supported in said member and engaging said 30 pinions whereby said shafts are caused to operate in unison; and joggers operatively connected to each shaft.

- 35 11. In jogging mechanism, jogger supports; joggers thereon; means for actuating the joggers on said supports; and means whereby the jogger support may be adjusted laterally without disarranging the jogger 40 actuating means.

12. In jogging mechanism; a set of jogger supports; joggers thereon; means for actuating the joggers on said supports; and means whereby the jogger supports may be 45 adjusted laterally while the machine is in operation without disarranging the jogger actuating means.

13. In jogging mechanism, having a receiving table or board; end and side joggers; 50 means for operating one set of joggers; connections whereby the other set of joggers is actuated from and with the first set; and means for adjusting the joggers to or from the table while the machine is in operation 55 without disarranging the jogger actuating means.

14. In sheet delivery mechanism having a receiving table or board, and means for delivering sheets thereon; of a set of joggers, supports therefor arranged above the table, means for reciprocating the joggers, and means whereby the joggers may be adjusted to or from each other while in operation above the table without disarranging 60 their operative mechanism.

15. In jogging mechanism having a receiving table; end and side joggers supported above the table; means for operating one set of joggers; connections whereby the other set of joggers is operated from and with the first set; and means whereby the joggers can be adjusted to or from each other while in operation above the table without disarranging their operating means. 70

16. In sheet delivery mechanism, a receiving table or board, joggers, jogger actuating mechanisms, and means whereby the jogger actuating mechanisms may be bodily adjusted toward or from each other without stopping the operation of the machine or disturbing the operative relation of the mechanisms. 75

17. In sheet delivery mechanism, a receiving table or board, joggers and jogger actuating mechanisms supported above the board, and means whereby the joggers may be bodily adjusted toward or from each other; without stopping the operation of the machine or disturbing the operative relation of the mechanisms; with means for 80 lowering the table beneath the joggers as a pile of sheets accumulates thereon. 85

18. In sheet delivery mechanism having a receiving table or board, joggers and jogger actuating mechanisms supported above the board, and means whereby the jogger mechanisms and joggers may be bodily adjusted toward or from each other while in operation without disarranging their operative relations; with means for 90 lowering the table beneath the joggers as a pile of sheets accumulates thereon. 95

19. In sheet delivery mechanism, a receiving table or board, joggers, jogger actuating mechanisms arranged to leave a free space between the mechanisms for the dropping of the sheets onto the table, and means whereby the jogger mechanisms may be bodily adjusted so as to move the joggers toward or from each other while in operation and without disarranging their operative relation. 105

20. In sheet delivery mechanism, a receiving table or board, joggers, jogger actuating mechanisms supported above the board and arranged to leave a free space between them for the dropping of the sheets between the jogger mechanisms onto the table, and means whereby the jogger mechanisms may be bodily adjusted so as to move the joggers toward or from each other while in operation and without disarranging their operative relation. 110 115

21. In sheet delivery mechanism, a receiving table or board, joggers, jogger actuating mechanisms supported above the board and arranged to leave a free space between them for the dropping of the sheets between the jogger mechanisms onto the table, and means whereby the jogger mechanisms may 120 125 130

be bodily adjusted so as to move the joggers toward or from each other while in operation and without disarranging their operative relation; with means for lowering the table beneath the joggers as a pile of sheets accumulates thereon.

22. In a sheet delivery mechanism having a receiving table or board, side joggers and supports therefor arranged above the table,

means for operating one set of joggers, operative connections whereby the other set of joggers is actuated from and with the first set and means whereby the joggers may be bodily adjusted.

In testimony that I claim the foregoing 15 as my own, I affix my signature.

MICHAEL ANDREW DROITCOUR.
